[57] CLAIM

An ornamental design for an instrument panel for a laser control console, as shown and described.

DESCRIPTION

FIG. 1 is a front elevational view of an instrument panel for a laser control console showing our design;

FIG. 2 is a bottom plan view thereof;

FIG. 3 is an end elevational view thereof, the opposite end elevational view being a mirror image;

FIG. 4 is a top plan view thereof; and

FIG. 5 is a rear elevational view thereof.

FIG. 1

FIG. 2

FIG. 3

FIG. 4
